UNITED STATES PATENT OFFICE.

ALEXANDER AIMWELL CANTIN, OF NEW YORK, N. Y.

DESIGN FOR A CAPITAL AND ARCHITRAVE.

44,084.

Specification for Design.

Patented May 27, 1913.

Application filed January 25, 1913. Serial No. 744,248. Term of patent 14 years.

To all whom it may concern:

Be it known that I, ALEXANDER AIMWELL CANTIN, a citizen of the United States of America, residing at New York city, borough of Manhattan, county and State of New York, have invented a new, original, and ornamental Design for a Capital and Architrave, of which the following is a specification, reference being had to the accompanying drawing, forming a part there-

of, which is a perspective view of a capital and architrave showing my new design.

I claim:

The ornamental design for capital and architrave, as shown.

ALEXANDER AIMWELL CANTIN.

Witnesses:

EUGENE J. CANTIN,
M. G. CRAWFORD.
